[57] CLAIM

The ornamental design for a hot/cold therapeutic compress, as shown and described.

DESCRIPTION

FIG. 1 is a front elevational view of a hot/cold therapeutic compress showing my new design;

FIG. 2 is a rear elevational view thereof;

FIG. 3 is a side elevational view thereof, the opposite side elevational view being similar to FIG. 3;

FIG. 4 is a top plan view thereof; and,

FIG. 5 is a bottom plan view thereof.
